CLAIM

The ornamental design for an “egg poacher,” as shown and described.

DESCRIPTION

FIG. 1 is a top, front, and right side perspective view showing our new design for an egg poacher.

FIG. 2 is a front view of the egg poacher shown in FIG. 1.

FIG. 3 is a rear view of the egg poacher shown in FIG. 1.

FIG. 4 is a right side view of the egg poacher shown in FIG. 1, the left side being a mirror image thereof.

FIG. 5 is a top view of the egg poacher shown in FIG. 1; and, FIG. 6 is a bottom view of the egg poacher shown in FIG. 1. The subject matter shown in dashed lines is for illustrative purposes and forms no part of the claimed design.

1 Claim, 6 Drawing Sheets
